LOCK DEVICE

Edward N. Jacobi, Milwaukee, Wis., assignor to
 Briggs & Stratton Corporation, Milwaukee,
 Wis., a corporation of Delaware

Application May 26, 1945, Serial No. 595,899

12 Claims. (Cl. 70—81)

1 This invention relates to locks and refers particularly to compartment door latch locks of the type shown and described in Patent No. 2,357,004, issued to Edward N. Jacobi, August 29, 1944.

Lock devices of this nature are usually mounted on the back of the compartment door near the free edge of the door and comprise a bored casing extending rearwardly from the door into the compartment. A lock cylinder rotatable and slideable in the casing bore and having a portion projecting through the door to the front side, thereof to act as a push button actuator for the cylinder controls the position of a latch bolt movably carried by the casing. Depression of the cylinder into the bore effects retraction of the latch bolt from engagement with a keeper on the wall of the compartment adjacent to the lock device and frees the door for opening.

In the past it has been customary to pivotally mount the lock bolt from the casing for swinging motion about an axis transversely of the axis of the lock cylinder and at the rear of the casing with the lock bolt extending forwardly toward the door but at a divergent angle to the casing for engagement of its free end behind a keeper mounted on the wall of the compartment adjacent to the lock device.

One of the most important prerequisites of door latch locks of this nature is to obtain secure latching action of the lock bolt with the compartment carried keeper so that the door can be positively locked in a closed position. Moreover, latching engagement should be such as to secure the door against either accidental opening as a result of vibration or by tampering with the door or lock in a deliberate attempt to effect unlatching.

Because of the pivotal mounting for lock bolts of many past types of compartment door locks, the forwardly projecting keeper engaging end of the bolt is caused to swing in an arc during motion thereof from an inoperative retracted position to an operative projected position which displaces the same a substantial distance rearwardly of the plane of the door. Because of such swinging motion of the lock bolt, it was heretofore necessary to mount the keeper at an acute angle to the plane of the door and with the lower edge of the keeper first engaged by the bolt during closing of the door disposed forwardly of the remaining portions of the keeper so as to allow the bolt to swing to its operative position behind the keeper.

Consequently, the bolt engaging surface of the keeper cannot lie squarely crosswise of the line of

motion of the lock device during opening of the door as is desirable, but sometimes lies at an angle of approximately 45° or less to said line of motion.

This condition is obviously objectionable especially in lock devices wherein the lock bolt is not positively held in its operative keeper engaging position but is yieldingly held in said position by spring means. In this latter event, it is frequently possible to effect unauthorized opening of the compartment door when the same is supposed to be locked closed by reason of the camming action of the lock bolt by the inclined surface on the keeper with which the lock bolt engages.

One of the objects of this invention is, therefore, to provide a compartment door lock device of the character described with a lock bolt mounted from the lock casing for substantially translating motion relative thereto in a substantially straight line path transversely of the casing axis so as to enable projection of the bolt to an operative position behind a keeper disposed substantially parallel to the plane of the door and squarely crosswise to the line of motion of the lock device during opening of the door.

Another object of this invention resides in the provision of a compartment door lock device having improved latching action so as to effectively preclude unauthorized opening of a compartment door to which the device is attached.

More specifically it is an object of the invention to provide a lock device of the character described with a substantially U-shaped lock bolt the legs of which straddle the lock casing and the closed end of which provides a keeper engaging bit, the surface of which is disposed in a plane substantially parallel to the door upon which the device is mounted, with the bolt supported from the casing by parallelogram linkage operable to restrain the bolt to substantially translating or straight line motion in a path substantially parallel to the plane of the door.

Another object of this invention is to provide a lock device with a substantially U-shaped lock bolt of the character described wherein the keeper engaging bit of the bolt may be offset to either side of the plane of the legs of the bolt any desired amount without detracting from secure latching action of the bit.

Still another object of this invention resides in the provision of a lock device of the character described with a substantially U-shaped lock bolt mounted from the casing for substantially translating motion in a path normal to the axis of the lock cylinder in said casing and to provide

a novel motion transmitting connection between the lock cylinder and lock bolt for translating depression of the lock cylinder into the casing into retractive motion of the lock bolt.

A further object of this invention resides in the provision of a door latch lock wherein a single spring serves both to bias the lock bolt to its operative projected position and to assure maintenance of the motion transmitting connection between the actuator of the device and the lock bolt.

With the above and other objects in view, which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claims.

The accompanying drawings illustrate one complete example of the physical embodiment of the invention constructed in accordance with the best mode so far devised for the practical application of the principles thereof, and in which:

Figure 1 is a longitudinal sectional view through a portion of a compartment, the door of which is provided with the lock device of this invention, and illustrating the lock bolt in its operative projected keeper engaging position;

Figure 2 is a view similar to Figure 1, but illustrating the manner in which depression of the lock cylinder into the casing bore retracts the lock bolt to its inoperative position;

Figure 3 is a bottom view of the lock device illustrated in Figure 1;

Figure 4 is a perspective view of the lock device of this invention showing the lock cylinder separated from the lock casing; and

Figure 5 is a longitudinal sectional view through the lock device to illustrate the manner in which the lock cylinder is mounted within the casing bore.

Referring now more particularly to the accompanying drawings in which like numerals indicate like parts throughout the several views, the numeral 5 designates the door of a glove compartment only the upper wall 6 of which is shown. Adjacent to the door opening at the front of the compartment the upper wall 6 is provided with a keeper or striker plate 7 extending down into the compartment with its rear surface 8 disposed substantially parallel to the plane of the door with the door in its closed position as illustrated.

A latch bolt 9 carried by the lock device of this invention, indicated generally by the numeral 10, has a keeper engaging portion 11 engageable behind the keeper and against the surface 8 thereof to secure the compartment door 5 closed.

The lock device 10 mounts on the rear of the door adjacent to its free edge opposite its hinge and for this purpose is provided with opposite laterally extending ears 12 carried by the lock casing 13 at the front thereof. The ears abut against the back of the door and suitable bolts passing through the ears and door hold the lock device assembled on the door in line with an aperture 14 in the door.

A lock cylinder 15 is slidable axially and rotatable within a bore 16 in the casing opening to the opposite ends thereof projects forwardly through the aperture 14 with the front end portion of the cylinder providing a push button actuator 15.

It will be understood that the lock cylinder 15

75

the lock bolt is thus mounted for substantially

is provided with the customary key operable tumblers as indicated at 17 in Figure 5 which permit rotation of the cylinder to locked and unlocked positions when a suitable key 19 is inserted into the keyway of the cylinder; and that the cylinder is secured against motion relative to the casing upon rotation of the cylinder to its locked position substantially 90° from its position illustrated in Figure 5. When the key is withdrawn in the locked position of the cylinder the tumblers project into opposite tumbler retaining grooves 20 in the casing communicating with the bore 16 thereof (only one of said grooves being shown in Figure 4).

The latch bolt 9 has a substantially U shape with its opposite legs 22 substantially straddling the rear portion of the casing. The closed end of the U-shaped bolt portion provides the keeper engaging bit 11, and it is to be noted that the legs of the bolt lie in a plane substantially normal to the casing bore, and that the keeper engaging surface of the bit 11 lies nearly parallel to said plane of the legs. The bolt is suspended from the casing by means of parallelogram linkage, indicated generally by the numeral 23, which restrains the bolt to substantially translating or straight line motion in a path parallel to the plane of the door and the legs 22 or normal to the casing bore.

As best shown in Figure 4, the linkage comprises two pairs of links 24 and 25 disposed alongside the top and bottom of the casing respectively. The link 24 has parallel opposite side arms 26 the forward extremities of which embrace bearing lugs 27 extending forwardly from the front of the casing near the top thereof to project slightly through the opening 14 in the door, and a hinge pin 28 passing through aligned apertures in the forward extremities of the arms 26 and the lugs 27 provide for pivotally mounting the link 24 for swinging motion on an axis normal to the lock cylinder axis and crosswise of the legs 22 of the lock bolt.

The side arms 26 of the link are connected by a strap 29 cooperating with the hinge pin 28 and the lugs 27 to rigidly hold the side arms in parallel relationship and against lateral deflection. The rear extremities of the arms 26 are individually pivotally connected with the legs of the lock bolt as at 30 adjacent to the junction of the legs 22 of the lock bolt.

The lower link comprises a substantially channel shaped plate the web 31 of which acts as a cover for the bottom of the lock device. Extending perpendicularly up from opposite sides of the web are opposite flanges 32 which are pivotally connected with the lower extremities of the legs 22 of the lock bolt as at 33.

The forward portion of the link 25 is also pivotally connected to the front end of the casing and for this purpose has apertures in the forward extremities of its flanges aligning with similar apertures provided in spaced bearing lugs 34 formed on the front of the casing and projecting forwardly into the hole 14 in the door so that a hinge pin 35 passing through these aligned apertures in the flanges and lugs mounts the link 25 for pivotal motion on an axis parallel to the axis of the hinge pin 28 but at the opposite side of the casing therefrom.

Since the links 24 and 25 are parallel and the center to center distances between the pivots 30 and 28 and between the pivots 33 and 35 are substantially the same, it will be understood that

5.

straight line or translatory movement to and from its operative projected position in a path substantially parallel to the plane of the door and transverse to the lock cylinder axis; and that the arms 26, legs 22, and flanges 32 at each side of the cylinder constitute parallelogram linkage by which this desired motion of the bolt is secured.

A torsion spring 36 coiled about the hinge pin 35 and having its end convolutions 37 and 38 hooked over portions of the casing and the link 25 respectively serves to yieldingly bias the link to a position with its rear portion swung inwardly toward the axis of the lock cylinder, and consequently yieldingly holds the lock bolt in its operative projected position as clearly illustrated in Figures 1 and 5.

Thus, it will be noted that the lock bolt is not positively held in its operative projected position, as in many past constructions, but is yieldingly maintained engaged behind the keeper 7 by its torsion spring 36, with assurance against unauthorized or accidental unlatching provided by the angular relationship between the engaging surfaces of the keeper and bit with respect to the line representing travel of the device during opening of the door. These surfaces of the lock bolt and keeper lie substantially squarely crosswise of the direction of force applied to open the door so as to preclude any camming action of the bolt out of its operative latching position.

The bolt is retracted to its inoperative position by inward depression of the lock cylinder into the casing bore, and for this purpose the cylinder is provided with a shoulder 40 on its side which engages with the extremity of a lever 41 formed as an upward extension of one of the flanges 32 on the lower link 25. The end portion of the lever is offset with relation to said flange so that its extremity contacts the side of the lock cylinder with the lever disposed exteriorly of the adjacent bearing lug 34.

Depression of the cylinder into its bore thus swings the link 25 on its hinge pin so that the rear end portion of the link swings away from the casing and pulls the lock bolt to its retracted inoperative position.

Attention is directed to the fact that the bearing lug 34 adjacent to the lever 41 lies between the flanges of the link 25 and that the flange opposite the lever 41 is positioned between the lugs 34 on the casing with the torsion spring confined under compression between the innermost flange and lug so as to exert a lateral force on the link 25 tending to yieldingly maintain the offset tip of the lever engaged with the side of the lock cylinder in the path of the shoulder thereon with a slight pressure. Accidental disruption of the motion transmitting connection between the cylinder, the link 25 and consequently the lock bolt due to looseness of the cylinder in the casing bore or deflection of the lever is thus precluded.

The torsion spring 36 thus not only reacts in a direction to unwind and thereby exert a biasing force through the link 25 onto the lock bolt for yieldingly holding the same in its operative projected position, but also serves as a compression spring to yieldingly hold the lever 41 engaged with the side of the lock cylinder.

The reaction of the spring between the casing and link to hold the link with its rear end portion connected with the lock bolt swung inwardly toward the cylinder axis also is translated through the lever 41 into an axial force on the cylinder to yieldingly maintain the same in an

6.

outwardly projected position defined by the engagement of a stop 43 carried by the cylinder at its rear portion with a ledge 44 on the casing.

The stop 43 forms a part of a tumbler spring retainer indicated generally by the numeral 45. The spring retaining element 45 has merely been indicated in Figure 5 and for a more complete disclosure of the same reference is had to the aforementioned patent to Edward N. Jacobi, No. 19,235,700, issued August 29, 1944.

Another highly important feature of this invention is the fact that a compact construction is afforded by utilizing a lock bolt having a U shape with the legs of the bolt substantially straddling the lock casing near the rear portion thereof. Because the legs of the bolt are spaced far enough apart, it is unnecessary to provide axial clearance between the cylinder and bolt in the depressed position of the cylinder for the inner rear portion of the lock cylinder projects between the bolt legs upon depression of the cylinder to effect bolt retraction.

If space permits, however, it will be understood that the lock bolt could easily be mounted rearwardly of the lock casing to provide clearance axially between it and the cylinder merely by lengthening the parallel links which pivotally support the bolt from the casing. In such an event, it would be desirable to join the opposite legs of the lock bolt by a wall normal to the casing bore and acting as a cover for the lock mechanism.

In the present case, however, a separate cover 46 is provided for the rear portion of the lock device. This cover has side walls 47 lying at opposite sides of the casing and directed toward the attaching ears 12 to be secured to the lock device upon attachment of the same to the rear of the door 5.

40 The rear wall 48 on the cover together with the side walls 47 and the web 31 of the link 25 guard the working parts of the lock device against interference with the contents of the compartment.

45 From the foregoing description taken in connection with the accompanying drawings, it will be readily apparent to those skilled in the art that the lock device of this invention has improved latching action and compactness; and that the keeper engaging bit of the bolt may be provided with any degree of offset with respect to the bolt to meet variations in the location of the keeper engaged thereby without in anywise requiring alteration of the bolt mounting or lock construction.

55 What I claim as my invention is:

1. In a lock device of the character described: a casing having a bore opening to its front end; a lock cylinder slidable axially in said bore with the front of the lock cylinder projecting out of the bore at the front of the casing to provide a push button actuator for the cylinder; a lock bolt having a keeper engaging bit; parallelogram linkage movably connecting the lock bolt with the casing and guiding the bolt for substantially translating motion in a path transversely of the cylinder axis, said bolt being movable in said path from an operative position with its bit projected to a keeper engaging position to an inoperative position with its bit retracted from said keeper engaging position; spring means yieldingly biasing the lock bolt to its operative projected position; and a motion transmitting connection between the lock bolt and the cylinder by which depression of the push button actuator to

slide the cylinder axially into the casing bore is translated into retractive motion of the lock bolt to its inoperative position.

2. In a lock device of the character described: a casing having a bore; an actuator slidable longitudinally in the bore with an end portion thereof projecting from the front of the casing to provide a depressible push button for the actuator; a lock bolt adjacent to the rear of the casing having a keeper engaging bit; parallelogram linkage pivotally connected with the casing adjacent to its front end and with the lock bolt so as to mount the bolt from the casing for substantially straight line motion of the bolt in a path transversely of sliding motion of the actuator; spring means reacting between the bolt and the casing for yieldingly maintaining the bolt in an operative position with its bit projected to a keeper engaging position; and a motion transmitting connection between the actuator and the lock bolt including an abutment on the actuator, and a lever arm on said linkage lying in the path of said abutment so that depression of the actuator into the casing bore acts through said lever and linkage to retract the lock bolt.

3. In a lock device of the character described: a casing having a bore; a substantially U-shaped lock bolt having its legs straddling the rear portion of the casing; a keeper engaging surface on the closed end portion of the bolt lying substantially parallel to the common plane of the legs of the bolt; an actuator for the bolt slidable longitudinally in the casing bore; substantially parallel links pivotally connected to the casing adjacent to the front end thereof and to said legs of the lock bolt and mounting the bolt for substantially translating motion with its legs travelling in a path transversely of longitudinal motion of the actuator; spring means reacting between the casing and the lock bolt for biasing the lock bolt to an operative projected position in which said keeper engaging surface thereof engages behind a keeper; and a motion transmitting connection between the lock bolt and the actuator by which depression of the actuator into the casing bore is translated into retractive motion of the lock bolt to an inoperative position in which its keeper engaging surface is disengaged from the keeper.

4. In a lock device of the character described: a casing having a bore opening to its opposite ends; an actuator slidable axially in said bore and having a portion projecting from the front of the casing providing a push button for the actuator; cooperating abutments on the casing and actuator for limiting axial motion of the actuator forwardly out of the casing bore but permitting depression of the actuator rearwardly into the bore so that the rear end of the actuator projects from the rear end of the casing; a substantially U-shaped lock bolt at the rear of the casing having its legs straddling a rear portion thereof and spaced sufficiently far apart as to permit projection of the rear end of the actuator therethrough in the depressed position of the actuator; pivoted links connected between the lock bolt and the casing and supporting the lock bolt for substantially translating motion in the plane of the legs of the bolt and substantially transversely of the axis of the casing bore; spring means yieldingly biasing the lock bolt to an operative projected position; and a motion transmitting connection between the lock bolt and the actuator by which depression of the actuator rearwardly into the casing bore is translated into

retraction motion of the lock bolt to an inoperative position.

5. In a lock device of the character described: a casing having a bore; a key operated lock cylinder rotatable in the bore between locked and unlocked positions and slidably axially in the bore in its unlocked position of rotation, the front of the lock cylinder projecting from the front of the casing to provide a push button actuator for sliding the cylinder axially in its bore; a substantially U-shaped lock bolt having its legs lying in a plane substantially normal to the axis of the casing bore and disposed at opposite sides of the casing at the rear thereof, the end portion of the bolt joining the legs being offset with respect thereto so as to lie at one side of the plane of the legs and providing a keeper engaging bit; two pairs of links, each pair having spaced connected side arms pivotally connected at one end thereof with the legs of the lock bolt and at their opposite ends with the lock casing adjacent to the front of the casing so as to provide parallelogram linkage at opposite sides of the casing with said links supporting the lock bolt from the casing for substantially translating motion in the plane of its legs, said bolt being movable from an operative projected position in which said bit is disengaged from the keeper; a motion transmitting connection between the lock cylinder and one of said pairs of links by which depression of the push button actuator to slide the lock cylinder axially into the casing bore is translated into retractive motion of the lock bolt to its inoperative position; and common means for yieldingly biasing the lock bolt to its operative projected position and for yieldingly holding the lock cylinder with its push button actuator projecting from the front of the casing.

6. In a lock device of the character described: a casing having a bore opening to one end thereof; an actuator depressible axially into said bore; a substantially U-shaped lock bolt having its legs embracing the rear portion of the casing and lying in a plane substantially normal to the axis of the casing bore, the closed end of the bolt defining a keeper engaging bit; a link pivotally connected between the legs of the lock bolt and the casing at the front end portion thereof so that the link extends longitudinally of the casing; means carried by the casing and cooperating with the lock bolt and said link to restrain the bolt to substantially straight line motion in a direction parallel to the plane of its legs upon motion of said link about its pivotal connection with the casing; a spring yieldingly biasing the lock bolt to an operative projected position in which its bit is engageable with a keeper; and a motion transmitting connection between the lock bolt and the actuator operable upon depression of the actuator into the casing bore to move the lock bolt to an inoperative retracted position in which its bit is disengaged from said keeper.

7. In a lock device of the type having a casing bored to slidably receive an actuator depressible into the casing bore to carry a lock bolt movably supported by the casing from an operative projected position to an inoperative retracted position with respect to a keeper with which the bolt is engageable; a shoulder on the side of the actuator; a lever pivotally carried by the casing and having a portion disposed alongside the actuator and in line with said shoulder so as to be engaged and pivoted thereby during depression of

the actuator into the casing bore; a connection between said lever and the lock bolt by which depression of the actuator into the casing bore is translated into retractive motion of the lock bolt; and a combination torsion and compression spring for biasing the lock bolt to its operative projected position and for yieldingly holding said portion of the lever against the side of the actuator so as to insure engagement of said shoulder therewith, said spring also acting on the actuator through said lever to yieldingly resist depression of the actuator into the casing bore.

8. In a lock device of the type having a casing bored to slidably receive an actuator depressible into the casing bore to carry a lock bolt movably supported by the casing from an operative projected position to an inoperative retracted position with respect to a keeper with which the bolt is engageable; bolt propelling means pivotally mounted on the casing and connected with the bolt so as to propel the same to and from an operative projected position upon pivotal motion thereof about its connection with the casing; interengaging parts on the side of the actuator and said bolt propelling means operable upon depression of the actuator into the casing bore for effecting retraction of the lock bolt to its inoperative position; means for biasing the lock bolt to an operative projected position through said bolt propelling means; and means for yieldingly maintaining said interengaging parts in cooperative relationship so as to insure bolt retractive motion upon depression of the actuator into the casing bore.

9. In a lock device of the character described: a lock body adapted to be mounted in a stationary position; a lock cylinder movably carried by the lock body and having key operated tumblers for controlling the motion of the cylinder; an elongated lock bolt having its body offset to pass beside the cylinder and having a keeper engaging bit at one extremity thereof engageable with a keeper in a projected position of the bolt; parallel links connected between the lock bolt and the lock body and constraining the bolt to endwise substantially straight line motion transversely of the axis of the cylinder; and a motion transmitting connection between the cylinder and the bolt operative to retract the bolt from its projected keeper engaging position by movement of the cylinder.

10. In a lock device of the character described: a lock body adapted to be stationarily mounted on the rear of a door; a lock cylinder movably mounted on the lock body and having key operable tumblers to control the motion of the cylinder; an elongated lock bolt having a keeper engaging bit at one end thereof in the axial region of the tumblers, said lock bolt being offset to pass beside the cylinder; parallel links spaced from the cylinder and extending rearwardly away from the door in the direction of the cylinder axis; pivotal connections between the forward ends of the links and the lock body; pivotal

connections between the rearward ends of the links and the lock bolt whereby said links constrain the bolt to endwise substantially straight line movement transversely of the cylinder axis; a spring for projecting the bolt in one direction toward a keeper engaging position; and means on one of said links engaged with the lock cylinder and through which movement of the lock cylinder in one direction is translated into retractive motion of the bolt to free the same from its keeper.

11. In a lock device of the character described: a lock body adapted to be stationarily mounted on a door; a lock bolt mounted on the lock body for movement substantially parallel to the door to and from a projected keeper engaging position in which the bolt latches the door closed; an arm pivoted on the lock body and connected with the bolt; an actuator guided in the lock body for movement from an inoperative position to an operative position and connected with said arm to transmit bolt retracting motion to the bolt through said arm by movement of the actuator toward its operative position; and a spring acting on said arm in a direction to project the bolt to its keeper engaging position and reacting on the actuator to yieldingly hold the same in its inoperative position.

12. In a lock device of the character described: 30 a lock body adapted to be stationarily mounted on a door; an actuator carried by the lock body for motion relative thereto in opposite directions; a lock bolt carried by the lock body for movement substantially parallel to the door toward and from 35 a projected keeper engaging position in which the bolt latches the door closed; means for imparting retracting motion to the bolt to free the same from its keeper including a pivot pin on the lock body, an arm on the bolt rotatably 40 journalled on said pivot pin and having a part disposed alongside the actuator, and a motion transmitting connection between the actuator and said part on the arm by which movement of the actuator in one direction is translated into 45 swinging motion of the arm to carry the bolt to a retracted position disengaged from its keeper; and a combined torsion and compression spring coiled about said pivot pin and reacting on the arm to yieldingly hold the bolt in its projected 50 keeper engaging position while urging the arm toward the side of the actuator.
